UNITED STATES PATENT OFFICE.

CLARENCE R. GRAHAM, OF NEWARK, CALIFORNIA.

COMBINED GAS AND COAL RANGE.

1,350,723.

Specification of Letters Patent. Patented Aug. 24, 1920.

Application filed September 15, 1919. Serial No. 323,823.

To all whom it may concern:

Be it known that I, CLARENCE R. GRAHAM, a citizen of the United States, and a resident of Newark, county of Alameda, and 5 State of California, have invented a new and useful Combined Gas and Coal Range, of which the following is a specification.

My invention relates to improvements in cooking stoves.

10 Since the general adoption of gas stoves for cooking purposes, it has been the practice to attach coal and wood burning stove units to gas stoves, primarily to heat the kitchens and adjacent rooms, and incidentally to provide additional cooking surface. These attachment units are generally known as kitchen heaters and are in themselves small stoves, usually supported by four legs.

20 To combine a gas stove with a kitchen heater, the heater unit is placed at one end or side of the gas stove and some means of attachment is employed to secure the stoves together so as to bring the fronts and cooking tops thereof into proper relation. If the gas stove has an oven vent pipe, such pipe is extended over and across the tops of the stoves and joined to the stove pipe of the heater, both pipes being plainly visible. 25

30 In instances where the heater has a gas, kindling or trash burning burner, a pipe connection thereto from the gas stove must be made.

In all, the advantages and conveniences 35 attending the use of a combined stove of the above type made up of separate stove units, are nearly eclipsed by certain disadvantages and objections such as, first, the provision of eight stove legs, six of which are 40 bunched at one end of the combined structure, which makes sweeping difficult, are unsightly, take up too much floor space, and render the structure cumbersome, second, the exposure of both stove and oven vent pipes 45 and the extension of the oven vent pipe over and across the cooking tops, which adds to the unsightliness and space consumption of the combined structure, and third, the necessity of matching the stove units as to size 50 so as to dispose the fronts and cooking tops in proper position, which means that a large number of attachment units or heaters of different styles and sizes must be made in order to be applicable to the many kinds and 55 sizes of gas stoves. The result of this last objection is that many misfit heaters are at-

tached and the tops and fronts of the gas stove and heater are not flush and cannot be as conveniently used or operated.

It is the primary object of my invention 60 to remove the hereinbefore noted objections and disadvantages in combined stoves of the kind hereinbefore discussed, by providing a combined gas and coal stove or range constructed in one single, compact, relatively 65 small unit and which is more durable, ornamental in appearance, simple as to construction, less expensive and takes up less room than stoves made up by attaching a kitchen heater to a gas stove. 70

Another object of my invention is to provide a combined gas and coal range of the character described, in which the frame elements are so constructed and arranged that, oven, broiler and warming chambers, gas 75 burners, a coal and wood fire box, warming shelves, cooking tops for the burners and fire box, and other stove elements, may be compactly arranged and related in a manner most convenient for their individual or 80 collective use, and so that a saving in space and material is provided.

A further object is to provide a stove of the character described in which the stove pipe and oven vent pipe are arranged so 85 that the vent pipe is entirely concealed, and the stove pipe is partly concealed and disposed in an inconspicuous and out-of-the-way position.

The invention possesses other features of 90 advantage, some of which, with the foregoing, will be set forth in the following description of the preferred form of my invention which is illustrated in the drawings accompanying and forming part of the specification. It is to be understood that I do not limit myself to the showing made by the said drawings and description as I may adopt variations of the preferred form within the scope of my invention as set forth in 100 the claims.

Referring to the drawings:

Figure 1 is a perspective view of a combined gas and coal range constructed in accordance with my invention.

Fig. 2 is a rear elevation of the range showing the arrangement of stove and oven vent pipes.

In construction my invention comprises a preferably horizontal rectangular bottom 110 stove frame 1 which consists of side bars 2 joined at their ends to end bars 3 and 4 and

supported at the joined ends by legs 5, 6, 7 and 8.

A horizontal cooking top frame 9, of preferably rectilinear outline, and comprising side bars 10 and 11 joined to end bars 12 and 13, is mounted in superposed preferably parallel relation to the bottom frame 1. The frame 9 is of preferably the same width as and of substantially two-thirds the length of the frame 1, and is arranged with the bar 12 at the outer end thereof, directly over and in line with the end bar 3 of the bottom frame.

An end wall 14 joins the aligned ends of the frames, being secured to the end bars 3 and 12 and to a rear wall 15 which is secured to the rear side bar 2 of the frame 1 and to the rear bar 11 of the frame 9. An end wall 16 is mounted between the bars 2 and secured to the wall 15 and bar 13 at the inner end of the frame 9. A bottom wall 17 is secured to the bottom frame 1 and closes that portion of the space between the frame bars of the bottom frame, that is located under the frame 9. These walls 14, 15, 16 and 17 support the frames in position.

Arranged between the aligned ends of the frames 1 and 9, and preferably occupying substantially one-third of the space between the frames is a fire box 18 for burning wood, coal and similar fuel. A fire box door 19 of the usual type is mounted to open and close on the front of the stove in the ordinary manner. A cooking top 20 having two holes therein closed by lids 21 is mounted in the frame 9 and closes the upper side of the fire box. A bar 22 joined at its end to the bars 10 and 11 of the frame 9 extends across the frame and with the bars 10, 11 and 12 supports the cooking top, in the ordinary manner. The fire box interior may be of any desired standard fire box construction and it is not thought necessary to illustrate or describe the detail construction of the box.

A vertical partition wall 23 secured to the side frame bars of the frames 1 and 9, and engaging the bottom wall, divides the space occupied by the fire box from the rest of the space between the frames and defines with the walls 15, 16 and 17 a warming chamber 24 which is open along the front side thereof to permit of access thereto.

Mounted just below the frame 9 within the confines of said frame are a plurality of gas burners 25 of standard construction. These burners are supported in the usual manner on pipes 26 leading thereto from a gas pipe 27 connected to a supply line, not shown, which pipe 27 extends along the front of the stove, being supported in brackets 28. The ordinary valves 29 are provided for the pipes 26. A grated cooking top 30 of the ordinary construction is supported in the frame 9 by the bars 10, 11, 13 and 22 of said

frame. The top 30 is arranged to lie substantially flush with the bars 10, 11, 12, 13 and 22 and the top 20, so cooking utensils may be conveniently and easily moved or slid from one top to the other. A drip pan 70 31 is mounted in the chamber 24 beneath the burners.

A stove element 32 is mounted on the bottom frame 1 on the end thereof opposite the fire box and is connected to the inner end of the frame 9 and extends above the frame. This element is divided horizontally, in a plane alining with the plane of the frame 9, by a wall 33 and forms a bake oven 34 in the upper portion thereof and a broiling 80 chamber 35 in the lower part. Suitable gas burners are arranged within the oven and broiler elements in this stove element, not shown, and as these constructions are well known and standardized they need not be 85 illustrated and described. Both the oven and the broiling chamber have downwardly opening doors 36 on the front sides thereof. The wall 16 may be considered as a wall of the broiling chamber and the wall 15 joins 90 with the rear wall 37 of said chamber where-as the outer wall 38 of said chamber may extend upwardly to form the corresponding wall 39 of the oven. A wall 40 extending as a continuation of the wall 16 constitutes the 95 inner side wall of the oven, and a wall 41 secured to the walls 39 and 40 and to a top wall 42 constitutes the rear wall of the oven. The top wall of the oven serves as a shelf and has an extension 43 which projects over 100 the cooking tops 20 and 30 to a point in line with the end of the frame 9 and serves as a shelf. A bracket 44 supports the outer end of this extension.

An upright wall 45 is secured to the walls 105 15 and 41 and extends above the frame 9 for the entire length thereof. This wall extends above the shelf or extension 43 for the length of said shelf and upper wall 42, is secured to said extension and supports the bracket 110 44. Substantially all of the walls of the stove are permanently connected and secured or engage one another so that the entire structure is rigid and strong, some of the walls serving as closures for separate 115 parts of the stove at some time. Like the walls, the stove elements are all interconnected and arranged to economize in space and to be readily accessible as well.

An oven vent pipe 46 is connected with 120 the oven 34 and chamber 35 in any suitable manner to create a circulation of air in said oven and chamber. This pipe extends from the back of the oven along the rear wall of the oven and behind the wall 45 to a flue 125 47 or stove pipe 47. The pipe 47 extends from the back of the fire box up behind the wall 45 through a guard member 48 secured to the back of the wall 45. The pipe 46 extends through the guard and is connected to 130

the pipe 47, the latter being connected with a chimney or flue, not shown. Thus, the vent pipe is entirely hidden from view from the front of the stove and the stove or flue pipe is partly hidden. A gas, kindling-burner 49 may be extended into the fire box from the pipe 27 which pipe extends in front of the fire box.

I claim:

10. 1. A combined gas and coal range having a bottom structure with corner legs, a fire-box in one end of the bottom, a top for said box, superposed baking and broiling ovens on the other end of said bottom and spaced horizontally from the fire-box to provide a chamber having an open front and a closed back therebetween, a set of gas burners arranged at the top of said chamber, a plane grating coplanar with the said top and above the gas burners, a drip pan below the burners and forming a top for said chamber between the said box and said ovens, one of the ovens being below and the other above the plane of said burners, and a gas service 35 pipe extending along the front of top struc-
15
20
25

ture and having a kindling burner to the fire-box.

2. A combined gas and coal range having a bottom structure with corner legs, a fire-box on one end of the bottom, a top for 30 said box, superposed baking and broiling ovens on the other end of said bottom and spaced horizontally from the fire-box to provide a chamber having an open front and a closed back therebetween, a set of gas burners arranged at the top of said chamber, a plane grating coplanar with the said top and above the gas burners, and a drip pan below the burners and forming a top for said chamber between the said box and said ovens, one of the ovens being below and the other above the plane of said burners. 35
40

In testimony whereof I have hereunto set my hand at Niles, California, this 5th day of September, 1919.

CLARENCE R. GRAHAM.
